UNITED STATES PATENT OFFICE.

JOSEPH M. MERROW, OF HARTFORD, CONNECTICUT, ASSIGNOR TO THE MERROW MACHINE COMPANY, OF HARTFORD, CONNECTICUT, A CORPORATION OF CONNECTICUT.

SHELL-STITCH MACHINE.

Application filed January 23, 1923. Serial No. 614,373.

To all whom it may concern:

Be it known that I, JOSEPH M. MERROW, a citizen of the United States, residing in the city of Hartford, county of Hartford, 5 State of Connecticut, have invented certain new and useful Improvements in Shell-Stitch Machines; and I do declare the following to be a full, clear, and exact description of the same, reference being had 10 to the accompanying drawings, forming a part of this specification, and to the characters of reference marked thereon.

This invention relates to overseaming machines and more particularly to machines 15 for forming shell stitch edging or border finish. On certain classes of work it is desirable to make the shells or clusters which characterize such finish very small and to apply them to an accurately trimmed edge 20 of material. Therefore, in connection with new varieties of shell stitch adapted for production in diminutive shells, my present invention has been developed and embodied in a machine of the Merrow overseaming 25 type provided with trimming mechanism and stitch forming instrumentalities including loopers in lieu of the latch needle which is commonly employed in shell stitch machines. The trimming mechanism operating 30 in advance of the stitching elements and simultaneously therewith prepares an even edge of material to receive the shell finish, and the latter by means of a suitable exchange of loopers may be made with either 35 two or three threads. The arrangement shown in the drawings is for producing the three thread finish.

In the drawings,—

Figure 1, is an end view of an overseaming machine of the Merrow type embodying 40 my invention.

Figure 2, is a view similar to Fig. 1, but showing only the lower part of the machine with certain parts removed and others 45 in section.

Figure 3, is a sectional view on line 3—3 of Fig. 1.

Figure 4, is a sectional view on line 4—4 of Fig. 1,—and

Figure 5, is a sectional view on line 5—5 of Fig. 1.

Like characters of reference designate like parts throughout the several views of the drawings.

Inasmuch as characteristic features of the 55 type of machine illustrated have been repeatedly set forth heretofore as in the United States Patent No. 734,987, issued to William H. Stedman, July 28, 1903, brief mention of many of the parts herein shown 60 will be sufficient to convey a clear understanding of the association therewith of the elements of the present invention. The stitching instrumentalities comprise the curved eye-pointed needle 1, upper looper 65 2, and lower looper 3. The needle receives its motion through the link 4, which connects the needle carrier 5, with an eccentric projection or stud 6, at the end of shaft 7. By mechanism (not shown) associated 70 with upper shaft 7 and lower shaft 8, looper 2, is actuated to reciprocate and oscillate so that it passes in a curved path extending above and below the needle plate 9, around one edge thereof, and looper 3, is reciprocated below the needle plate. The needle moves to cooperate with the lower looper below the needle plate and with the upper looper above the needle plate and the 75 loopers below the plane of the needle plate 80 move to cooperate with each other in a well known manner to form overedge stitching. The upper looper may be throated in form to engage a loop of thread from the lower looper, or it may be provided with an eye, 85 as shown, to carry a thread of its own. The throated form of looper, sometimes called a spreader, serves to carry a loop of the lower looper thread into a position above the material to be entered by the needle and the 90 eye form of looper serves to carry a loop of its own thread through a loop of the lower looper thread and into a position above the material to be entered by the needle. The variety of finish produced 95

when the throated form of looper is used is composed of two threads while that produced by the other form of looper is composed of three threads, in either case, in the resulting finish, each thread engaging loop 100 of each thread, extends through but one loop of another thread, and this peculiarity marks a distinguishing difference between the new varieties of shells made by the machine embodying the present invention and the shells made by machines using a latch needle instead of loopers.

The tensions, take-ups and thread guides

illustrated, serve their usual purpose in a manner that will be readily understood to those familiar with the sewing machine art,—this is also true of the presserfoot and 5 presserfoot mechanism, therefore these parts need not be described in detail.

Parts of trimming mechanism such as commonly employed in the type of machine illustrated, are shown in Figs. 1, 2 and 4. 10 Such mechanism, which is actuated in a well known manner, includes the lower cutter 10, and upper cutter 11, which cutters cooperate to cut off or trim the edge of the work adjacent to one side of 15 the needle plate, slightly in advance of the needle. Both cutters are adjustable in the usual manner, so that the line of trimming, or distance of the cutters from the line of needle penetration, may be varied.

20 Feed mechanism for advancing the work at intervals of several cycles of the stitch forming instrumentalities and especially constructed for practical association and cooperation with mechanism of the type 25 of machine illustrated will now be described. The feed dog actuating mechanism employed includes a pivoted carrier wherein the feed dog is mounted for reciprocatory movement. Movement pivotally 30 of the carrier, intermittently causes an engagement of the feed dog with the work during movement of the feed dog effective for advancing the work, and as will hereinafter more fully appear, the reciprocations of the feed dog are synchronized with the stitch forming cycles so that the movement for advancing the work can occur only while the needle is disengaged therefrom, and it will also appear that engagement 35 of the feed dog with the work occurs only at intervals of several stitch forming cycles so that the needle will penetrate the work repeatedly substantially at the same point thereby producing a shell or cluster 40 of stitches.

The feed dog 14, is provided with a shank 15, for sliding association with a suitable carrier 16, the latter being channeled at 17, to receive the feed dog shank 50 and pivoted at 18, to a bracket 19, which also supports the work plate 20. Lateral support is provided for the feed dog carrier by side walls of the slot 21, in which it is pivoted and also by contact with the block 55 22, (see Figs. 2 and 3) secured as by screws 23, at the end of the machine frame 24. The feed dog 14, is also laterally supported by the block 22, and maintained thereby in its guiding channel 17, in carrier 16.

60 Mechanism for actuating the feed dog and that for actuating its carrier is associated with the main shaft 8, beneath the work plate and is enclosed in a housing formed by the lower cutter support 25, the flanged bearing block 26, and cover

plates 27 and 28, which are secured to said bearing block, cover plate 28, being held by the knurled screw 29, and extended into a finger piece 30, so that it may be readily removed to permit access to the parts 70 covered thereby.

Means for reciprocating the feed dog and adapted through a sliding pivotal connection to permit the movement imparted thereto by its carrier, include a lever arm 31, having a hub 32, pivotally supported on a stud shaft 33, which extends through the bearing block 26. At its free end, lever arm 31, is forked to engage a flanged block 34, which is pivotally carried by a pin 35, rigid with the feed dog and extending through an aperture 36, in the feed dog carrier. The required movement of lever 31, is derived from an eccentric 37, on shaft 8, and transmitted through link 38, and stud 39, the latter being enlarged at 40, between the lever and link to form a shoulder for maintaining the link in alignment with its eccentric. The length of stroke imparted to the feed dog is controlled by adjusting stud 39, in slot 41, of lever 31, the slot engaging part 42, of the stud which is flattened to prevent its turning, being extended and threaded at 43, to receive nut 44. It will be noted that slot in lever 31, is of arcuate form and so related to the eccentric 37, that adjustment of stud 39, in said slot will not materially alter the position of the feed dog at the forward end of its range of movement, the variation in the stroke occurring at the other end thereof.

From the foregoing it will be clear that the feed dog is reciprocated once for each reciprocation of the needle, that is to say, once for each cycle of the stitch forming implements. It follows that in producing a shell composed of several stitches secured at practically the same point, the feed dog must effect advance of the work only at intervals of several stitch forming cycles. This result as before intimated is accomplished by moving the feed dog carrier in a manner to cause the feed dog to engage the work once for each several reciprocations thereof. Suitable means for thus moving the feed dog carrier include an element 45, mounted for rotation on shaft 46, which is supported by bearing block 26. In its lateral face, and adjacent the feed dog carrier, element 45, is provided with cam groove 47, to receive cam roll 48, which is supported on stud 49, slotted at 50, for a purpose that will hereinafter appear. The stud 49 is extended at its rear end in the form of an eccentric shank 52, adapted to be adjustably held in a depending part of the feed dog carrier by screw 54. The cam groove 47, by virtue of the described relation of parts between it and the feed dog,

determines the position of the feed dog vertically with respect to the work plate. For each revolution of the cam, the feed dog is moved into position to engage the work, and 5 in order that this action may occur at desired intervals, the cam element 45, is provided with gear teeth 55, which mesh with the pinion 56, formed at the end of shaft 8. The driving relation between this pinion and gear may be in any suitable ratio,— that illustrated is five to one, in which case 10 the feed dog engages the work to advance it after each five cycles of the stitch forming implements, thereby forming a shell stitch edge composed of shells of five stitches each. The amount the feed dog teeth are projected above the work plate may be regulated within suitable limits by adjusting the eccentric stud 49, which, with the screw 54, 15 loosened, may be turned by a screw driver introduced through holes 58 and 59, respectively in the flange of bearing block 26, and the cam and gear element 45.

It will be seen that the trimming mechanism must embody cutting edges which will, during the time the work is practically stationary, cut a length of the edge which is as great or slightly greater than the length of the long feed which occurs between successive clusters of stitches, and in this connection it will be noted that the feed dogs should always start their work feeding movement at practically the same time with relation to the trimmer operation, and stitch forming operation regardless of the distance between groups of stitches, such desirable result being accomplished by the shape or curvature of the slot 41.

Having thus described my invention, what I claim is,—

1. In a shell stitch overedging machine comprising stitch-forming mechanism and feeding mechanism associated to form clusters of stitches at successive spaced points on the work, the combination of trimming mechanism comprising cutters operating in consonance with the stitch-forming and feeding mechanisms, located adjacent the feeding and in advance of the stitch forming mechanism, said trimming mechanism having cutting edges of a length no less than the distance between clusters of stitches formed by the stitch-forming and feeding mechanisms.

2. In a shell stitch overedging machine comprising stitch forming mechanism and feeding mechanism associated to form clusters of stitches at successive spaced points on the work, the combination of trimming mechanism comprising cutters operating in consonance with the stitch forming and feeding mechanisms, said cutters having cutting edges of a length no less than the greatest distance between clusters of

stitches, and means for adjusting the length of movement of the feeding mechanism forwardly in the direction of feed from a point substantially fixed with relation to the trimming mechanism. 70

3. In an overedge sewing machine the combination with stitching instrumentalities including a needle, an upper looper and a lower looper, of feeding mechanism including a feed dog, means for actuating the feed dog to advance the work at intervals of several cycles of the stitch forming elements to form clusters of stitches, and trimming mechanism in advance of the stitching elements having cutting edges of 80 a length equal to or greater than the distance between clusters of stitches. 75

4. In an overedge sewing machine in combination with a support for work, feeding mechanism including a reciprocating feed 85 dog, a carrier in which the feed dog is mounted to reciprocate and itself mounted to oscillate about a fixed axis, means for reciprocating the feed dog in its carrier, means including a gear provided with a cam groove for oscillating the feed dog carrier to position the feed dog above the work support, a stud having an eccentric shank for associating the feed dog carrier with the cam groove and means for permitting adjustment of the stud to vary the amount of projection of the feed dog above the work support. 90 95

5. In an overedge sewing machine, feeding mechanism including a feed dog, a carrier in which the feed dog is mounted to reciprocate and itself mounted to oscillate about a fixed center, means for reciprocating the feed dog in its carrier including an eccentric and lever disposed on opposite sides of the carrier, a link associated with the eccentric and a stud for connecting the link with the lever, the latter being provided with an arcuate slot to permit adjustment of the stud therein to thereby vary at one end the length of stroke imparted to the feed dog. 100 105 110

6. In an overedge sewing machine, feeding mechanism including a feed dog, a movable carrier in which the feed dog is mounted to reciprocate, means for reciprocating the feed dog including an eccentric and a lever located, respectively, on opposite sides of the carrier and contiguous thereto and a link pivotally connected with the lever and eccentric for transmitting motion from the eccentric to the lever. 115 120

7. In an overedge sewing machine, feeding mechanism including a feed dog, a pivoted carrier in which the feed dog is mounted for reciprocation, and means for reciprocating the feed dog which include motion transmitting elements contiguous to and affording guiding support on opposed sides of the carrier. 125 130

8. In an overedge sewing machine, the combination in feeding mechanism, of a feed dog, a pivoted carrier in which the feed dog is mounted for reciprocation, means including an eccentric for reciprocating the feed dog located on one side of the carrier and means including a gear for oscillating the feed dog carrier located on the other side of the carrier and an operating shaft for the eccentric and gear extending beneath the carrier.
9. In an overedge sewing machine, the combination in feeding mechanism, of a feed dog, a pivoted carrier in which the feed dog is mounted for reciprocation, means for reciprocating the feed dog comprising a shaft, an eccentric on the shaft, a link on the eccentric, a pivoted lever, and suitable connections between the link and lever and the lever and feed dog, and means for oscillating the carrier comprising a pinion on the shaft, a cam grooved element having gear teeth in mesh with the pinion and suitable connections between the cam groove and the

carrier, the eccentric and link being on one side and the pinion, gear element and lever on the other side of the carrier.

10. In an overedge sewing machine, feeding mechanism including in combination a shaft supported in a bearing of the machine frame and projecting therebeyond, an eccentric on the shaft adjacent to the end of the machine frame, a pinion at the end of the shaft, a feed dog carrier pivoted at one end for oscillation in a plane extending at right angles to the axis of the shaft and lying between the eccentric and the pinion, a feed dog mounted for reciprocation on the feed dog carrier, a pivoted lever for reciprocating the feed dog, a gear in mesh with the pinion and having a cam groove, means on the feed dog carrier for engaging the cam groove and means for transmitting motion from the eccentric to the lever.

In testimony whereof I have signed my name to this specification.

JOSEPH M. MERROW.
